CLAIM

The ornamental design for a wireless earbud, as shown and described.

DESCRIPTION

FIG. 1 is a perspective view of a wireless earbud showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view showing the wireless earbud of FIG. 1 inserted into a charging case with another earbud. The broken lines shown in FIG. 8 depict environment and form no part of the claimed design.

1 Claim, 8 Drawing Sheets(56)
